AAGE NYROP, OF HORSHOLM, DENMARK

APPARATUS FOR ATOMIZING LIQUIDS.

Application filed July 25, 1925, Serial No. 46,170, and in Denmark July 25, 1924.

The present invention relates to an apparatus for atomizing liquids.

In atomizing liquids it is known to conduct the liquid to be atomized to a rapidly revolving disc on which the liquid, under the influence of the centrifugal force and according to its viscosity and elasticity will be spread out in form of a thin film. It is also known to atomize liquids by blowing them by aid of compressed air through a small orifice or slit.

It is the object of this invention to construct the apparatus forming the subject matter of the present invention in such a manner that its operation may be considered as a combination of the two known methods of working mentioned, and by such combination a special effect may be secured.

The apparatus is characterized chiefly by an upper inverted stationary hollow truncated conical conduit, the lower edge of which is sharp, and a lower dish coaxial with said cone, arranged to be revolved at a high speed and having its inside turned out to a paraboloid form. The upper edge of this lower dish is likewise made sharp and is disposed slightly below the said lower edge of the cone, the diameter of the dish being substantially that of the discharge end 25 of the conduit, so that there will always remain between the cone and the dish a comparatively narrow gap through which the liquid to be atomized will be thrown by centrifugal force.

The accompanying drawing is a vertical sectional view showing the apparatus described in a constructional form.

1 is a stationary, inverted hollow truncated conical conduit, the lower edge 2 of which is made sharp. Beneath this inverted hollow cone 1 is disposed, coaxially therewith, a concave plate or dish 3, the inner surface of which is turned out to a paraboloid, the upper edge 4 of this dish being likewise made sharp. This edge is disposed a little below the knife edge 2 of the inverted cone 1 and is, in the constructional form shown in the drawing, immediately below this edge 2. The arrangement may, however, also be so that the upper edge 4 of the dish is disposed slightly within or slightly outside of the lower edge 2 of the inverted cone. The dish 3 is secured to a spindle 5 which is vertical and coaxial to the dish and the inverted cone. This spindle may, as shown, extend upwards through the inverted cone 1, or it may extend down-

ward from the dish, and may by suitable gearing be made to revolve at a high speed. By this arrangement a narrow gap is produced between the stationary inverted cone 1 and the dish 3 revolving with spindle 5, through which gap the liquid to be atomized can emerge. In the constructional form shown in the drawing the liquid to be atomized is conducted into the dish 3 through a special supply pipe 6. The arrangement may, however, also be such that the spindle 5 is made hollow and that it serves at the same time as liquid supply pipe. Whether one or the other of these arrangements be employed, the conditions should be such that the liquid runs into the dish as near as possible to its axis whereupon it will from this point be deposited in the deepest portion of the dish. By suitable means compressed air 75 is introduced into the inverted cone 1, and, as shown in the drawing, the flow of the compressed air has been indicated by arrow.

The operation of the apparatus is as follows:

The liquid which is conducted to the dish will when the dish revolves at a high speed, spread in an even film over the inner surface of said dish, partly under the action of the centrifugal force, partly owing to the 85 paraboloid form of that surface which causes a suction downwards along the spindle 5 and a blast outwards at the upper edge 4.

Furthermore the compressed air, introduced into the apparatus, will act on the liquid by producing within the gap between the lower edge 2 of the inverted cone and the upper edge 4 of the dish a ring of highly compressed air, the lower side of which will be revolved with the dish 3, while its upper 95 side will be pressing against the stationary cone 1 and will therefore be practically stationary. These peculiar conditions will have the effect that the compressed air emerging through the gap will, outside of the latter, 100 form eddies in the air. The film of liquid spread on the paraboloid surface of the dish will emerge from apparatus through the said gap partly under action of the centrifugal force and partly under the force of the compressed air, and the liquid or the film of liquid leaving the apparatus is immediately subjected to a violent disruption as it becomes mixed with the air and passes from the high pressure prevailing within the apparatus into the low pressure outside of the latter. The thereby produced fine particles

of liquid are, therefore, partly owing to the eddies mentioned, and partly owing to the fact that the liquid itself will immediately on its emerging from the apparatus be exposed to a peculiar effect produced by the combined action of the rapidly revolving dish and the stationary cone, individually made to rotate on their own axes. This rotation of the fine particles of liquid has the effect of producing a singular arrangement of their molecules. It is therefore possible to arrange, that the fine particles thus produced by the atomizing effect may each individually be enveloped by a thin film of a preserving medium, which has been added to the liquid, and which has a greater specific gravity than the same.

By varying the volume of compressed air supplied in proportion to the width of the gap it is possible to regulate the rotation of the fine particles of liquid mentioned and thereby also the arrangement of the molecules of liquid within the individual particles. The said rotation may even be made so great that the individual particles of liquid are again exposed to a disruption (a secondary disruption) so that by such means the atomizing effect will be a specially fine one.

By suitably choosing the materials of which the dish and the inverted cone are

made it may, furthermore, be possible to expose the liquid to a strong electric action at the moment when it is emerging through the gap between the inverted cone and the dish. This may for many liquids have a high conserving value, and it also has an influence on the placing of the molecules within the individual particles of liquids.

Having now particularly described and ascertained the nature of my said invention and in what manner the same is to be performed, I declare, that what I claim is:

1. An apparatus for atomizing liquids, comprising in combination, a concave plate, means for supplying compressed air to said plate, said means comprising a truncated conical conduit tapering toward said plate and terminating in proximity to said plate, the diameter of the end of said conduit adjacent the plate being substantially equal to the diameter of said plate and in coaxial alignment therewith, means for supplying a liquid centrally of said plate, and means for rotating said plate.

2. An apparatus as claimed in claim 1 said plate being parabolic in section.

3. An apparatus as claimed in claim 1 said plate and the discharge end of the conduit being provided with sharpened edges.

AAGE NYROP.
